UNITED STATES PATENT OFFICE.

FRANK SEDLAK, LOUIS SEDLAK, AND ALBERT HORA, OF CHICAGO, ILLINOIS.

FUEL-IGNITING DEVICE.

1,052,624.

Specification of Letters Patent. Patented Feb. 11, 1913.

Application filed October 18, 1912. Serial No. 726,449.

To all whom it may concern:

Be it known that we, FRANK SEDLAK and LOUIS SEDLAK, citizens of the United States, and ALBERT HORA, a subject of the Kingdom 5 of Bohemia, and residents of Chicago, in the county of Cook and State of Illinois, have invented certain new and useful Improvements in Fuel-Igniting Devices; and we do hereby declare that the following is 10 a full, clear, and exact description thereof, reference being had to the accompanying drawings, and to the letters of reference marked thereon, which form a part of this specification.

15 This invention relates to a fuel igniting device more especially for use in starting coal fires without kindling wood, paper or the like and consists of the matters hereinafter described and more particularly 20 pointed out in the appended claims.

The object of the invention is to produce a device of the kind particularly adapted for use with cook stoves, and one which will be simple of construction, economical to 25 manufacture and at the same time highly efficient for the purpose intended.

In the drawings:—Figure 1 is a view representing a vertical central section through the grate and apron of a cook stove showing 30 our improved igniting device in position ready for starting a coal fire therein. Fig. 2 is a view representing on an enlarged scale a top plan of our improved igniting device with one of the burner tips shown in 35 horizontal cross-section. Fig. 3 is a view representing a vertical central section through the device in a plane indicated by the line 3—3 of Fig. 2.

Referring now to the drawings, the improved 40 igniting device is mounted on a standard 10 having an extended base 11. As shown, the standard 10 is tubular, being secured to the base in any familiar manner, and is threaded at its upper end to receive 45 a finishing cap 12.

On the standard is mounted a horizontally extending, vertically adjustable burner member provided with nozzles adapted to be inserted between the grate bars so as to 50 discharge a hot flame against the fuel in the grate. 13 indicates the said burner member as a whole, the same being secured to the standard 10 and being constructed and arranged as follows:—14 indicates a 55 cross-fitting comprising, as shown, a vertical tubular member 15 which fits slidably upon

the standard 10, and two oppositely placed, laterally extending branch tubes 16, 16. 17 indicates a handle-bar which may be of any suitable construction to fit the hand for 60 grasping it and has a threaded end 17^a which is screwed into one of the branch tubes 16, and is brought into rigid engagement with the standard 10. Said bar thus constitutes a handle and at the same time 65 means for locking or clamping the cross-fitting 14 upon the standard. The other branch tube 16 of the cross-fitting is connected to the burner member as will appear and is screw-threaded to receive a threaded 70 plug 18 which closes its inner end against the escape of gas. A coupling sleeve 19 is threaded into the outer end of said branch tube by means of which there is connected to it one end of a T-fitting 20 to which is 75 coupled a controlling valve 21, and a rubber hose or other flexible connection 22 leading from the source of gas supply. The end of the T-fitting 20 opposite the coupling 19 is threaded to receive a pipe 23 which leads 80 directly to a nozzle member 24. The pipe 23 has a jet nozzle 25 fixed in its end adjacent the controlling valve 21 and air ports 26, 26, adjacent the same in the manner of a Bunsen burner. The effective area of said 85 ports is controlled by means of a sliding ring 27 on the pipe 23. To the end of the pipe 23 is secured a nozzle piece having, as shown, three nozzles 28. The three nozzles are connected to said pipe 23 by a cross-fitting 29. The three nozzles are arranged 90 in a horizontal plane with the jet orifices at their ends adapted to discharge the gas in such manner as to produce a horizontal sheet of flame which will rise upwardly at a 95 distance from the nozzles and thus attacking the bottom layer of fuel and also rising through the body of the same, produce ignition in a minimum of time.

Our improved ignition device is operated 100 in the following manner: The standard is placed with its base 11 on the apron 30 of the stove 31, as shown in Fig. 1. The burner member 13 is adjusted up or down, (the handle 17 being first unscrewed to permit 10 the adjustment,) until the burner nozzles 28 are brought into a plane slightly above the grate bars and generally below the body of fuel in the grate. The standard is then moved into such a position as to present the 110 nozzles at the desired points, as shown. The gas is then turned on and ignited. By ad-

justing the ring 27, a blue hot flame is produced which hastens ignition of the fuel. Long flames are shot from the nozzles across or under the bottom layer of coal thus producing a sheet of flame which rises through the body of the fuel, ignites it and thus starts the fire.

It will be noted that our improved ignition device is so constructed and arranged that when in use the burner openings or orifices will be presented in a horizontal direction instead of upwardly and there is no danger of any ashes, coal dust or the like falling from the grate and clogging said orifices. The features by which the burner member is made vertically adjustable renders it possible to adapt the device to any kind of a cook stove or grate and the particular means providing the adjustment whereby the adjustment is produced by means of the handle that is used for placing the device in position for use, makes the production of the adjustment readily and quickly accomplished.

We claim as our invention:—

1. A fire starting device comprising a portable upright standard having a base adapted to rest on the apron of a stove, a substantially horizontal burner member provided with a plurality of laterally spaced horizontally directed nozzles adapted to discharge in a substantially horizontal plane, means for mounting said burner member on

said standard so that said burner member is capable of vertical adjustment, and a handle member, said handle member operating in conjunction with said means and standard to lock said burner member in adjusted position on said standard.

2. A fire starting device comprising a portable upright standard having a base adapted to rest on the apron of a stove, a substantially horizontal burner member provided with a nozzle adapted to discharge in a substantially horizontal plane, a cross tubular fitting having a vertical member slidingly mounted on said standard and oppositely disposed horizontal threaded branch tubes, a handle threaded into one of said branch tubes and engaged against said standard to clamp said cross-fitting thereto, a plug closing the inner end of the other branch tube, means connecting said last named branch tube with the inlet end of said burner member, and a valve casing communicating with said connecting means.

In testimony, that we claim the foregoing as our invention, we affix our signatures in the presence of two witnesses, this 15th day of October, A. D. 1912.
